UNITED STATES PATENT OFFICE.

JOSEPH C. GARNER AND WILLIAM GUTMAN, OF DETROIT, MICHIGAN.

BRANDING-IRON.

1,157,687.

Specification of Letters Patent.

Patented Oct. 26, 1915.

Application filed May 20, 1915. Serial No. 29,342.

To all whom it may concern:

Be it known that we, JOSEPH C. GARNER and WILLIAM GUTMAN, citizens of the United States, residing at Detroit, county 5 of Wayne, State of Michigan, have invented a certain new and useful Improvement in Branding-Irons, and declare the following to be a full, clear, and exact description of the same, such as will enable others skilled 10 in the art to which it pertains to make and use the same, reference being had to the accompanying drawings, which form a part of this specification.

Our invention relates to an electric branding iron shown in the accompanying drawings and more particularly pointed out in the following specification and claim.

One of the objects of our invention is to provide an iron of simple and inexpensive 15 construction in which the branding die is in the form of a substantially flat disk supported in the open end of a chambered casting fitted with a handle for convenience of operation;—the heating element being constructed in the form of a helically wound 20 spool of wire located adjacent to the reverse side of the branding die and covering its entire surface to provide for the uniform heating of the die.

Another feature of the invention consists 25 in providing an annular guard surrounding the casting supporting the branding die, that the operator may be protected against accidental contact with its heated surface, the annular guard being perforated to admit 30 the circulation of the air therethrough, that it may remain cool.

Other advantages and improvements will hereafter appear.

In the drawings:—Figure 1, is an elevation of the device fitted with a cord and plug for connection with an electric light socket. Fig. 2, is a longitudinal sectional view of the device. Fig. 3, is a cross-sectional view of the device on line 3—3 of 40 Fig. 2. Fig. 4, is an end elevation of the branding iron showing the face of the die. Fig. 5, is a fragmentary sectional view of the device showing a modification of the 45 manner of securing the branding die to the chambered casting.

Referring now to the letters of reference placed upon the drawings:—A, denotes a handle provided with a ferrule having an 50 annular screw-threaded stem B, engaged with a chambered casting C.

D, indicates a heating element consisting of a spool of helically wound wire, the convolutions being separated by suitable insulation in the usual manner.

E, E', denote wires connected with the heating element inclosed in the cable E', extending through the handle and provided with a plug F, for connection with an electric light socket.

G, indicates a plurality of screws in the wall of the casting C, to secure the heating element in position.

H, designates a branding die consisting of a flat metal disk secured in the open end 70 of the casting by a bolt I, having a screw-threaded engagement with the die and with the disk H', of the heating element. The die may, however, be supported as indicated in the modification shown in Fig. 5, in 75 which screws I', extending through the wall of the chambered casting engage the die.

h, denotes lettering or other arbitrary symbols employed on the obverse side of the die. They are formed in casting, or may 80 be cut therein as desired.

It will be noted that the heating element is positioned so as to cover the entire reverse face of the branding die, to insure a complete and uniform heating of the latter that 85 the brand made thereby, may be clear and legible throughout.

J, designates a heat resisting insulation surrounding the heating element inclosed by the chambered casting.

K, denotes a perforated guard shell spaced from the chambered casting having a screw-threaded engagement with the ferrule carried by the handle.

It will be obvious that the perforated 95 guard surrounding the chambered casting will permit the circulation of air between the casting and the guard shell, that the latter may be kept relatively cool, and to protect the operator from injury through accidental contact with the hot casting. It will be apparent by employing a die and a heating element of the form shown, the latter may be brought into adjacent relation with the die and cover its entire inner face insuring a uniform temperature throughout, and a brand of clear and legible character.

Having thus described our invention what we claim is:—

An electrical branding device, including a 110 handled or manually actuated member, a cable housed within said handled member, a

chambered casting, a septum or disk separating the latter into compartments, one compartment containing a heat-resisting insulation, a heating element within the other compartment of said casting, said heating element having connection, by means of conductors extending through said cable, with a source or medium of electricity, a branding die secured to the bottom edges of the open end of said casting, the securing means for said branding die comprising a bolt threaded into said septum and die, and a perforated guard-shell spaced from, and inclosing said casting, the upper

end of said guard-shell being adapted to be connected to said handled or manually actuated member, said septum or disk having passages therethrough for said conductors for making connection with said heating element.

In testimony whereof, we sign this specification in the presence of two witnesses.

JOSEPH C. GARNER.
WILLIAM GUTMAN.
